FOOD STORAGE AND DISPLAY DEVICE

Edward M. Stiles, Burlington, Iowa

Application October 2, 1939, Serial No. 297,567

8 Claims. (CL 62—89.6)

My invention belongs to that class of devices used for the storage, preservation and display of foodstuffs.

An object of my invention is to provide a food display and storage means which will eliminate many of the disadvantages of existing equipment.

More particularly, it is an object of my invention to provide a structure in which dehydration of the contained foods is eliminated.

A further object of my invention is to provide a food storage and display cabinet construction wherein a number of individual display or storage cells may be provided, and in which access to any one of the cells can be had without loss of cold air from any parts of the cabinet other than the particular cell.

Another object is to provide a refrigerated display cabinet structure in which opening of the cabinet for removal or insertion of foodstuffs does not permit any inrush of warm air to the front glass of the cabinet. Fogging and frosting of the glass is thus eliminated.

Still another object is to provide a structure wherein the air to which the stored foodstuffs are exposed is isolated from the air which passes over the refrigerant coils and deposits its moisture in the form of frost on the coils.

Another object is to provide a food storage cabinet having storage cells therein, each of which can be removed as a unit, together with its contents, if desired. This facilitates handling of the goods, and greatly increases the ease with which the storage cabinet, and the individual cells, can be cleaned.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a perspective view of a refrigerated display cabinet embodying my invention.

Figure 2 is a rear elevation of the cabinet shown in Figure 1.

Figure 3 is a vertical sectional view on the line 3—3 of Figure 2.

Figure 4 is a fragmentary vertical sectional view on the line 4—4 of Figure 3.

Figure 5 is a fragmentary horizontal sectional view on the line 5—5 of Figure 3; and

Figure 6 is a perspective view of one of the food storage and display cells which constitute a part of my invention.

On the drawings I have used the reference

numeral 10 to indicate generally a casing. This may be of a type similar to refrigerated display cases now in common use in grocery and meat stores, constructed with walls of insulating material 12 which may be cork or any other suitable material. In the front of the case 10 is provided with a plurality of glass windows 14 to give visibility of the interior. The casing is provided with coils 16 and 18 which may be the expansion coils of a conventional mechanical refrigeration system or may contain circulating brine or other cooling medium. At the rear of the case 10 are sliding doors or panels 20, 22, 24 and 26. The sliding panel 20 overlaps the panel 22 and the panels 20 and 22 are mounted in guide ways 28 which permit horizontal sliding movement. The panels 24 and 26 are similarly arranged.

As thus far described, the cabinet 10 and its fittings involve no substantial differences from commercial display cases now in common use. My invention consists in the provision in such a display case of food storage cells or compartments indicated generally by the letter C. A perspective view of one of these cells is shown in Figure 6. It consists of a top member 30, side walls 32 and a bottom 34, all preferably formed of sheet metal. The front of the cell C is truncated to conform to the slope of the window 14 in the case 10 and this truncated portion of the cell C is provided with a window 36, which is mounted in any suitable manner and may be made of glass or other transparent material. The rear of the cell C is closed by a back 38 which extends outwardly beyond the wall members 30, 32 and 34 in the form of a flange 40. Access to the interior of the cell C is made possible by a door 42 mounted on hinges 44 which are preferably spring hinges, so that the door 42 will be self-closing when released. If ordinary plain hinges are used, a latch or similar retaining means 46 may be provided for holding the door 42 in closed position and will preferably have a knob 48 which can be grasped for opening the access door 42.

A number of cells C, constructed as above described, are mounted within the case 10, being supported in any suitable manner. As an example, I have shown in the drawings transverse structural members 50, which support members 52 and 54 extending longitudinally of the base 10. The members 54 are notched as at 56 to receive the cells C and to aid in spacing the front ends thereof. The cells C are thus supported by the members 52 and 54.

The back 38 of the cell C is preferably located

just slightly forward of the inside plane of the rear wall of the case 10, to allow the proper clearance between the sliding panel 22 and the projecting portions of hinges 44 and knob 48. Inside the rear face of the case 10 I provide inwardly extending flange members 58. In the space between adjacent cells C, the flanges 58 are continued as a portion 59. The members 58 and 59 abuttingly engage the flanges 40 on the cells C and provide a connection or seal through which practically no flow of air will occur when the cells are in place.

Access to the interior of a particular cell C is obtained by sliding the panel 20 or 22 aside so that the door 42 of the desired cell can be opened. It will be noted that when this is done the interior portions indicated generally as A) of the cabinet 10 are not opened to the external atmosphere in any way, because of the seal effected between the portions 58 and 59 on the inside of the rear face of the case 10 and the flange portion 40 on the cell C. Any loss of cold air occurs only from the particular cell C which is open.

It will be further noted that access can thus be gained to the food storage space without admitting any room air to the space A which would fog or frost the front glass 14. Such fogging detracts from the neat appearance of the case, and obstructs the customers' view of the goods displayed within.

A third significant and important advantage of the structure described arises from the fact that refrigeration of foodstuffs kept inside the cells C is accomplished without any contact between the air to which the foodstuffs are exposed and the cooling coils 16 and 18. It is well known that the air in space A is continuously dehydrated by deposit of its moisture on the coils 16 and 18. In the normal circulation in a conventional box, the air thus dehydrated extracts moisture from the stored foodstuffs, and this undesirable cycle goes on continuously. The result is that moisture is removed from meat, causing both a loss of weight and discoloration. Vegetables become wilted, rubbery and discolored. Consequently there is a serious item of expense represented by spoilage, even in a refrigerated storage cabinet.

By isolating the food storage space in the cells C I eliminate the disadvantages above indicated. Cooling of the interior of the cells C is accomplished by conduction through the walls 30, 32 and 36, but obviously moisture is not removed through the walls from the interior. The air in space A which is dehydrated by the coils 16 and 18 does not mix with the air within the cells C. The result is that I can display foodstuffs such as fresh meat and vegetables, and keep them in fresh, attractive and saleable condition over much longer periods than is possible with the conventional structures. Elimination of the losses through storage spoilage cuts down costs which must otherwise inevitably be passed on to the consumer. Consequently, with my equipment food prices can be lower, because they need not include the dead weight of mark-ups to include spoilage. Furthermore, the customer is assured of receiving foods which have fresh feel and taste.

In the lower part of the case 10 I provide cells C' which are quite similar to the display cells C used in the upper portion of the case, as to wall and access door construction, but with a plain sheet metal front member 62 instead of the window 36. At the rear edge they have an outwardly extending flange 40, which effects a seal

5 by engaging portions 58 and 59, just as in the case of the C type cells.

The cells C' can be used for storage of surplus foodstuffs or other goods prior to selling.

It may be desirable, for example, to arrange a display of certain goods in the compartments C, in which the display is visible to customers through the windows 14 and 36. The stock of goods for sale, corresponding to those arranged in display in any particular cell C, can be kept in the cell C' immediately below. Any necessity for disarranging the display is thus avoided, yet the sale stock is kept conveniently available. As in the case of the cells C, the cells C' are supported and spaced in such a way that a free circulation of air from the space A may take place around and between them.

It will be noted that the cells C and C' can be entirely removed from the cabinet 10 simply by sliding them rearwardly out of the cabinet when the proper panels 20 or 22, etc. are open. This facilitates cleaning and other maintenance both of the cells themselves and of the interior of the case 10. Extra cells C' containing food products may be stored in a walk-in cooler or other auxiliary refrigerated space which may be available in a store, and can be transferred or interchanged with those in the case 10 as may be desired. The members 52 and 54 are connected by rods 60 which serve as runners to facilitate the insertion and removal of the cells C and C'.

It has been pointed out that the construction of my cells C and C' avoids dehydration of food products in the cells by preventing contact of the air in the space A with the foods. This same construction gives rise to another important advantage in that the amount of moisture in each cell can be regulated as desired. For products which require a high degree of moisture to preserve their freshness, the air in the cell in which those products are kept can be heavily loaded with moisture by any suitable means. For the products displayed in other cells, which do not require so much moisture, the moisture can be independently regulated in those cells to meet the requirements.

My invention gives greatly improved results in the preservation of fruits and vegetables when on display. The cool temperatures maintained by the structural combination which I have developed prevent decay and growth. The retention and regulation of the moisture in the cells prevents dehydration. The combination of the two, low temperature and retention of moisture, prevents wilting. Furthermore, when wilted and shriveled vegetables are sprinkled with water and placed in a display cell in my device, their crispness and garden freshness are in a large measure restored.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. A food storage device comprising an outer casing, refrigerant means therewithin, a transparent window in one wall thereof, a plurality of openings therein, compartments adapted to be inserted into said casing through said openings, and windows in said compartments adjacent said window in said casing when said compartments

are inserted in said openings, each of said compartments having an outwardly extending member around one end, said member effecting an abutting engagement with the wall of said casing when the compartment is inserted through one of said openings therein. 5

2. Food storage means comprising a refrigerated casing, an opening in a wall thereof, a box-like storage cell insertable into said casing through said opening, and means adapted to effect a seal between said cell and said casing around said opening, said seal substantially preventing egress of air from the space within said casing outside of said cell, said last means comprising a flange surrounding said opening, secured to the inner wall of said casing, and extending toward the center of said opening, and a second flange constituting an extension of one wall of said cell, said flanges having abutting engagement when said cell is inserted into said casing. 10

3. Means for the display of food products comprising a casing, a transparent window therein, individual unit cells insertable into said casing through openings therein, transparent portions in said cells located adjacent said window when said cells are inserted into said casing, and means surrounding each opening adapted to effect an air seal with the cell in said opening, to prevent ingress of room air and fogging of the interior surface of said window. 15

4. Refrigerated display means comprising a casing, a transparent window therein, compartments within said casing, transparent portions in said compartments located in alignment with said window for vision therethrough, said compartments each having one wall adjacent a wall of said casing, openings through said adjacent walls of said casing and said compartments allowing access to said compartments, and means effecting a seal between said compartments and the wall of said casing surrounding said openings in said casing to prevent ingress of room air to the space between said window and said transparent portions. 20

5. Refrigerated storage display means comprising an outer heat-insulated cabinet, refrigerant means therein, a transparent window in the front wall thereof, a plurality of compartments located in heat-exchanging relation with 25

each other within said cabinet, said compartments having imperforate heat conducting walls preventing exchange of air between the interior of said compartments and the interior of said cabinet surrounding said compartments, transparent windows in the front walls of said compartments, spaced from the window in said outer cabinet, and an access opening in each compartment coacting with an opening in the wall of said cabinet. 30

6. A food storage device comprising an outer casing, a transparent window in one wall thereof, a plurality of openings in the opposite wall thereof, storage cells insertable into said casing through said openings, and windows in the ends of said cells adjacent the window in said casing, the length of said cells being proportioned so that when they are fully inserted in the casing, an air space remains between the cell windows and the casing window. 35

7. In a food storage cabinet, an outer casing, a window in one wall thereof, a plurality of horizontally spaced openings in the opposite wall thereof, storage cells removably inserted into said casing through said openings, the length of said cells from front to back being less than the interior distance between the walls of said casing above mentioned, and the width and height of said cells being less than the length thereof, windows in the inner ends of said cells, doors in the outer ends of said cells, means effecting a seal between said casing and said cells, preventing loss of air from the interior of said casing when the door to a cell is opened, and a refrigerant coil extending longitudinally of said casing above said cells. 40

8. Means for the display of food products comprising a casing, a transparent window therein, individual unit cells insertable into said casing through openings therein, and transparent portions in said cells located adjacent said window when said cells are inserted into said casing, said cells having imperforate heat conducting walls preventing exchange of air between the interior of said cells and the interior of said cabinet surrounding said cells, said cells being in heat-exchanging relation with each other when inserted in said casing. 45

EDWARD M. STILES.
